Charles G. Metcalf, Taunton, Mass., assignor to
Reed and Barton Corporation, Taunton, Mass.,
a corporation of Massachusetts

Application August 19, 1953, Serial No. 26,520

Term of patent 14 years

(Cl. D54—12)

To all whom it may concern:

Be it known that I, Charles G. Metcalf, a citizen of the United States, residing at Taunton, in the county of Bristol and the Commonwealth of Massachusetts, have invented a new, original, and ornamental Design for a Spoon or Similar Article, of which the following is a specification, reference being had to the accompanying drawing, forming a part hereof.

In the drawings:

Figure 1 is a front elevational view of a spoon embodying my new design and

Figure 2 is a side elevational view of said spoon.
Figure 3 is an enlarged cross-sectional view taken on line 3—3 of Figure 1.

I claim:

The ornamental design for a spoon or similar article, as shown.
